CONTAINER FOR FISHING TACKLE AND THE LIKE

Leonard J. Ligon, Glendale, Calif.

Application April 3, 1948, Serial No. 145,508

Term of patent 14 years

(Cl. D58—13)

To all whom it may concern:

Be it known that I, Leonard J. Ligon, a citizen of the United States and a resident of Glendale, California, have invented a new, original, and ornamental Design for a Container for Fishing Tackle and the like, of which the following is a specification, reference being had to the accompanying drawing, forming part thereof.

Referring to the drawing:

Figure 1 is a perspective view of a container for fishing tackle and the like, with the cover in open position, showing my new design;

Figure 2 is a top plan view of the container with the cover closed;

Figure 3 is an end elevation as seen from the right of Figure 2;

Figure 4 is a front elevation;

Figure 5 is a bottom plan view of the container;

Figure 6 is an elevation of the end of the container opposite that shown in Figure 3; and

Figure 7 is a rear elevation of the container.

I claim:

The ornamental design for a container for fishing tackle and the like, as shown.

LEONARD J. LIGON.
